UNITED STATES PATENT OFFICE.

LAWRENCE S. SCHMIDT, OF PITTSBURGH, PENNSYLVANIA.

PULVERIZED-FUEL FEEDER.

1,342,135.

Specification of Letters Patent.

Patented June 1, 1920.

Application filed May 11, 1917. Serial No. 167,897.

To all whom it may concern:

Be it known that I, LAWRENCE S. SCHMIDT, a citizen of the United States, residing at Pittsburgh, in the county of Allegheny and 5 State of Pennsylvania, have invented certain new and useful Improvements in Pulverized-Fuel Feeders, of which the following is a specification.

The prime objects of the present invention 10 are to provide a new and improved pulverized fuel burner of simple and efficient construction; new and improved fuel feed means whereby a greater feeding force is imparted to the fuel than has heretofore 15 been possible; and means for effecting a thorough atomization of the fuel.

With these objects and others in view, my invention is embodied in preferable form in the constructions and arrangements herein- 20 after described and illustrated in the accompanying drawings.

In these drawings,

Figure 1 is a vertical section of the feeding structure and mechanism of the burner.

Fig. 2 is a detail section on the line 2—2 of Fig. 1.

Fig. 3 is an edge view of the air pressure element illustrated in Fig. 2.

Fig. 4 is a section on the line 4—4 of 30 Fig. 1.

Fig. 5 is a vertical section of a modified form of the invention employing a positively driven impeller element in connection with a source of low pressure air.

Fig. 6 is a detail front elevation of the impeller element shown in Fig. 5.

Fig. 7 is a detail edge view of the element shown in Fig. 6.

Fig. 8 is a vertical section of another 40 modified form of the apparatus showing the combination of a source of low pressure air with a combined propeller and impeller element driven by a current of high pressure air.

Referring to the drawings and first to the construction illustrated in Figs. 1 to 4 inclusive, 1 is a bin adapted to contain the coal dust, powdered coal or prepared pulverized coal and which communicates with a substantially vertical gravity-feed fuel conduit pipe 2 in which is mounted a valve 3 adapted to control the supply of fuel. The pipe 2 communicates with a casing 4 preferably forming part of the main burner structure and this casing is prolonged laterally and horizontally to provide a vacuum cham-

ber 5 adjacent the inner horizontal end of the casing, and fuel passageways 6 are provided between the outer wall of this casing and the wall of a conoidal body providing a 60 chamber 7, these walls being connected by webs 8. The passageways 6 lead to the chamber of a nozzle 9 which communicates at its outer end with a burner (not shown). The chamber 7 communicates at its outer end 65 with a longitudinal passageway 10 in which is mounted a pipe 11 adapted to communicate with a source of high pressure air, such as a compression and impeller pump of the turbine type and which is not herein shown. 70 The inner end of the chamber 7 is provided with a head 12 through which extend longitudinally a series of small apertures 13, by means of which the air passes from the chamber to the nozzle, in parallelism to the 75 fuel through the passageways 6.

Mounted in the nozzle just beyond the head of the chamber and over the fuel outlets is a freely rotatably mounted combined propeller and impeller member 14 which is 80 carried loosely on the bolt 15 fixed to the head 12. This member is preferably of the type shown in Figs. 2 and 3 which illustrates a rotor having both propeller and impeller elements and operating on the turbine principle and in which 16 is an inner series of turbine blades adapted to receive the high pressure air from the chamber 7 whereby the member is driven and which is provided with an outer concentric series of 90 turbine blades 17, which constitute impeller elements and which act to create a vacuum adjacent the fuel outlets and in the space 5 of the casing 4 and thereby produce a suction on the fuel of greater force than that 95 which would be produced by the mere draft of the current of air past the fuel.

In the operation of the device shown in Figs. 1 to 4 inclusive, the fuel is fed down the pipe 2 and air under high pressure is 100 admitted to the chamber 7, whence it passes through the small passageways 13 and strikes axially against the inner blades 16 of the air pressure member 14 revolving said member in a high rate of speed and creating a vacuum in the chamber 5 immediately adjacent said member which will have the effect of sucking in the fuel with great violence through the opening 6 into the chamber of the nozzle in which the air and fuel 110 will be thoroughly commingled and the fuel pulverized into fine particles which will be

effectively carried along by the stream of air, through the nozzle and toward the burner. The rotary member 14 will also serve to mechanically disintegrate and scatter the fuel.

It will be seen that this arrangement provides a vacuum creating device within the nozzle and immediately adjacent the junction of the feed pipe with the nozzle, where-
10 by a powerful suction and disintegrating action is exerted upon the air and fuel, as distinguished from apparatus in which a natural draft or a forced draft from a pressure device located at a distance from
15 said junction of the fuel and air, is provided.

In Figs. 5 to 7 inclusive, a construction is shown in which the vacuum creating element is shown as used in connection with a source 20 of low pressure air. In this arrangement the said element is provided with impeller blades only and is adapted to be positively driven by mechanical means from an external source of power, in order to produce
25 the necessary pressure for the creation of the vacuum in the adjacent end of the feed chamber.

Referring to this construction, 18 is the conduit for the low pressure air which may 30 be conducted by natural draft from the atmosphere or from air heating apparatus or a non-compressing fan. This low pressure air leads directly into the nozzle through a connecting elbow pipe section 19. 20 is the
35 nozzle. Formed in the elbow fitting 19 is a fuel receiving casing 21 with which communicates the lower end of a fuel pipe 22. Passageways 23 lead from the chamber 21 into the nozzle. A conoidal body 24 corre-
40 sponding to the body 7, constituting the air chamber in the device of Figs. 1 to 4, is formed in the casing 21 and in this body and in the wall of the casing is mounted a driving shaft 25 which is adapted to be
45 suitably connected to positively driving mechanical means at its outer end and which at its inner end within the nozzle and adjacent the fuel openings 23 is provided with a driven member 26 having impeller ele-
50 ments 27.

In the operation of the device of Figs. 5 to 7 inclusive, the low pressure air enters through the pipe 18 and elbow 19 and thence passes into the nozzle and the fuel is fed
55 down the pipe 22 into the chamber 21. The impeller element being positively driven from the source of external power creates a vacuum in the feed chamber 21 which will produce a strong suction feed on the fuel
60 and a powerful disintegrating and scattering action thereon.

It will be seen that the general form of the structural parts of the apparatus of Figs. 5 to 7 inclusive, corresponds to that
65 of the apparatus of Figs. 1 to 4. Thus for

the high pressure air pipe 11 inserted in the opening 10 in the casing of the latter construction, the shaft 25 of Figs. 5 to 7 inclusive is employed in connection with the same structure of casing. To some extent, therefore, the parts are interchangeable.

In Fig. 8, a construction is shown in which the combined propeller and impeller vacuum creating member of Fig. 1 is illustrated in conjunction with a source of low 75 pressure air and in which such member is adapted to be driven by high pressure air as in Fig. 1, instead of by a positive drive from an external source of mechanical power as in Fig. 5. In this ar-
rangement, 28 is the fuel pipe, 29 the fuel feed chamber in the casing forming part
80 of the feeder structure, 30 an air chamber communicating with a high pressure air pipe 31 and 32 is a low pressure pipe com-
municating with the nozzle 33. At the end
85 of the chamber 29 and over the fuel open-
ings 34 and the air openings 35 is rotatably mounted the combined propeller and im-
peller air member 36 which is of the double 90
turbine type having two series of blade ele-
ments, as illustrated in Figs. 2 and 3. This
member is adapted to be driven by the high
pressure air coming through the pipe 31, to
thereby create a suction on the chamber to 95
which the fuel is fed. The main body of
air supply for mixing with the fuel is ob-
tained through the low pressure air pipe.

What I claim is:—

1. In means for feeding pulverized fuel, 100 the combination with a source of fuel supply, a casing having a closure provided with a fuel outlet passage, a nozzle in advance of the closure, an air supply pipe in communication with the nozzle, a rotor member dis-
posed in advance of and adjacent the closure, said rotor member having impeller means 105 for creating a vacuum to exert a suction upon the fuel within the casing.

2. In means for feeding pulverized fuel, 110 the combination with a source of fuel supply, a casing having a head provided with a fuel outlet passage, a nozzle in advance of the head, an air supply pipe in communication with the nozzle, a rotor member secured 115 to the head, said rotor member having im-
peller means for creating a vacuum to exert a suction upon the fuel within the casing.

3. In means for feeding pulverized fuel, 120 the combination with a source of fuel supply, a casing having means to form an in-
terior chamber, and a closure for the casing provided with a fuel outlet passage, a nozzle in advance of the closure, an air supply pipe in communication with the nozzle, a 125 rotor member disposed adjacent the closure, said rotor member having impeller means for creating a vacuum to exert a suction upon the fuel within the casing.

4. In means for feeding pulverized fuel, 130

the combination with a source of fuel supply, a casing having means to form an interior chamber from which the fuel is excluded, and a closure for the casing provided 5 with a fuel outlet passage and a passage in communication with the interior chamber, a nozzle, an air supply pipe in communication with the nozzle, a rotor member disposed adjacent the closure, said rotor member having 10 impeller means for creating a vacuum to exert a suction upon the fuel within the casing.

5. In means for feeding fine coal, a fuel supply pipe, an air supply pipe, a casing having a head provided with independent 15 outlet passages for fuel and air, a nozzle having a common chamber with which the outlets communicate and a rotary member of the turbine type having propeller and impeller means mounted beyond the outlets.

20 6. In means for feeding fine coal, the combination with a fuel supply pipe, an air supply pipe adapted to supply air to mix with the coal, a rotor member having propeller and impeller blades concentrically arranged, 25 said member mounted in advance of and adjacent to the fuel outlet, and means for driving said member by air under high pressure.

7. In means for feeding fine coal, in combination with a fuel pipe, an air supply pipe,

30 a nozzle, a casing intermediate said pipe and nozzle and having a head provided with fuel outlet passageways, a chamber body located in said casing and in communication with a source of high pressure air and having air outlets leading to the nozzle and a combined 35 propeller and impeller member mounted in the nozzle beyond the fuel and air outlets and adapted to receive the pressure of the stream of air and to create a vacuum on the fuel outlets.

40 8. In means for feeding fine coal, in combination with a fuel supply pipe, an air supply pipe in communication with a source of low pressure air, a mixing chamber with which the outlets of said air pipe and fuel pipe communicate, a combined propeller and impeller member located adjacent the fuel outlet and adapted to create a vacuum to maintain a suction on the fuel and a source of high pressure air in communication with 45 said member to drive the same.

In testimony whereof I affix my signature in presence of two witnesses.

LAWRENCE S. SCHMIDT.
